DESIGN FOR A SHOE

Alfred Johnson, Chicago, Ill.

Application December 6, 1940, Serial No. 97,110

Term of patent 7 years

To all whom it may concern:

Be it known that I, Alfred Johnson, a citizen of the United States, residing at Chicago, in the county of Cook, State of Illinois, have invented a new original, and ornamental Design for a Shoe, of which the following is a specification, reference being had to the accompanying drawing, forming a part thereof, and in which

Figs. 1 and 2 are opposite side views of the shoe, slightly in perspective, showing my new design.

I claim:

The ornamental design for a shoe, as shown.

ALFRED JOHNSON.
